UNITED STATES PATENT OFFICE.

WILLIAM J. PITTS, OF PLYMOUTH, ENGLAND.

LIFE-BOAT.

1,117,439.

Specification of Letters Patent.

Patented Nov. 17, 1914.

Application filed June 30, 1914. Serial No. 848,132.

To all whom it may concern:

Be it known that I, WILLIAM J. PITTS, a subject of the King of Great Britain, and residing at Plymouth, England, have invented 5 certain new and useful Improvements in Life-Boats, of which the following is a specification, such as will enable those skilled in the art to which it appertains to make and use the same.

10 This invention relates to life boats, and the object thereof is to provide an improved device of this class which will be safe in use and which may be injured seriously by inward bulging of the hull in any place, or 15 which may be entirely cut or broken in two and will still remain afloat; a further object being to provide a boat of the class specified which is simple in construction and comparatively inexpensive but which possesses 20 all the qualities necessary to preserve life in case of shipwreck under any conditions.

The invention is fully disclosed in the following specification, of which the accompanying drawing forms a part, in which the 25 separate parts of my improvement are designated by suitable reference characters in each of the views, and in which:—

Figure 1 is a plan view of the hull portion of my improved life boat with the deck 30 and all the super-structure removed; Fig. 2 a central longitudinal section thereof on the line 2—2 of Fig. 1; and, Fig. 3 a cross section on the line 3—3 of Fig. 1.

In the accompanying drawing the hull 35 structure only is shown, this being all that is necessary in order to fully illustrate my present invention, but it will be understood that, in practice, the hull is entirely covered by a deck having the usual superstructure 40 and hatches or hatch-ways.

The hull *a* of my improved life-boat is made entirely of metal plates and within the hull and extending entirely around the sides, bow and stern of the hull is a main side hull 45 air compartment *b* divided by transverse partition plates *b*² forming supplemental air compartments *b*³, and centrally and longitudinally of the hull is a main central air compartment *c* divided by transverse partition plates *c*² into supplemental central air compartments *c*³ and entirely inclosing the main central longitudinal air compartment *c*, and within the main side hull air compartment *b* is an elliptical open space *d*.

The bottom of the main side hull air compartment *b* and the outer side wall thereof are formed by the walls of the hull of the boat, as shown at *a*² in Fig. 3, and the bottom of the main central longitudinal air compartment *c* is also formed by the bottom 55 of the hull as shown at *a*³.

The space *d* around the main central longitudinal air compartment *c* is open at the top and provided with a floor *d*² supported by transverse angle-irons *d*³ riveted to the 65 bottom of the hull and to each other and to the corresponding walls of the compartments *b* and *c*, or these angle-irons may be secured in position in any desired manner.

The bottom of the hull is also provided 70 with two equally spaced keel plates *e* which are T-shaped in form in cross section and riveted to the hull, and the bottom of the hull is also reinforced centrally and longitudinally by butt-straps *e*². The transverse 75 partition plates *b*² of the air compartment *b* which extends entirely around the hull are provided with flanges riveted to the sides and bottom of the hull, as shown at *b*⁴, and the top and inner side walls of the supplemental air compartments *b*³ into which the 80 compartment *b* is divided are formed by continuous plates *b*⁵ having flanges which are riveted to the partition plates *b*² at the top thereof, and also the inner edges thereof as shown at *b*⁶, and said continuous plates are also provided with flanges which are 85 riveted to the side and bottom walls of the hull at *b*⁷.

The top and side walls of the supplemental compartments *c*³ into which the central main longitudinal compartment *c* is divided are formed by continuous plates *c*⁴ having flanges which are riveted to the top 90 and side edges of the transverse partition plates *c*², as shown at *c*⁵, and the plates *c*⁴ are also provided with flanges which are 95 riveted to the bottom walls of the hull at *c*⁶.

The partition plates *b*² which divide the main side air compartment or compartments *b* are extended upwardly in the form of triangular plates or extensions *b*⁸, as shown in Fig. 3, and riveted to the hull all around the boat, said hull being extended above the compartment or compartments *b*, 100 as clearly shown in said figure, and the hull is also provided at the top thereof with a 105 guard rail *f* and any desired number of

transversely arranged seats g may be employed, the ends of which may be supported on angle pieces g^2 riveted to the hull, or the sides thereof, and said seats may also be provided with supplemental supports g^3 arranged on, or secured to the top of the central longitudinal compartment c .

It will be understood that my improved life boat may be made of any desired size, and the seats g may be used, if desired, to strengthen the hull, or the sides thereof transversely, but a boat, the hull of which is made in the manner herein shown and described, will possess all the necessary strength against both longitudinal and transverse strain and if broken or cut in two, the separate parts thereof will float and remain safe.

If a boat made in this manner should be injured by the forcing in of the hull at any point, or the breaking or cutting in two thereof, so as to admit water freely to the space d , the boat or the separate parts thereof would still remain afloat when fully loaded, it being understood that the size or capacity of the air compartments b and c is made such as to accomplish this result, and while I have shown and described the preferred detail of the construction of my improvement, it will be understood that changes therein and modifications thereof may be made, within the scope of the appended claims, without departing from the spirit of my invention or sacrificing its advantages.

Having fully described my invention,

what I claim as new and desire to secure by Letters Patent, is:—

1. A life boat having a main side hull air compartment extending entirely around said hull on the inner side thereof and divided by transverse partitions into supplemental compartments, and a main central longitudinal air compartment separated from the main side hull air compartment by an open space extending entirely around it, said main central longitudinal air compartment being also divided by transverse partitions. 40 45

2. A life boat having a main side hull air compartment extending entirely around said hull on the inner side thereof and divided by transverse partitions into supplemental compartments, and a main central longitudinal air compartment separated from the main side hull air compartment by an open space extending entirely around it, said main central longitudinal air compartment being also divided by transverse partitions, the outer side and bottom walls of the main side hull air compartment being formed by the 50 55 hull of the boat and the bottom of the main central longitudinal air compartment being also formed by the bottom of said hull. 60

In testimony that I claim the foregoing as my invention I have signed my name in 65 presence of the subscribing witnesses this 9th day of June, 1914.

WILLIAM J. PITTS.
